(57) **CLAIM**

We claim the ornamental design for a portion of module for clinical laboratory automation system, as shown and described.

DESCRIPTION

FIG. 1 is a front, top and right side perspective view of a portion of module for clinical laboratory automation system showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The broken lines in all drawing views are included for the purpose of illustrating portions of the module for clinical laboratory automation system that form no part of the claimed design.
